DESIGN FOR A CONVERTER FOR SUCTION CLEANERS

George W. Walker, Pleasant Ridge, and Kenneth A. Hopkins, Pontiac, Mich., assignors to Eureka Vacuum Cleaner Company, Detroit, Mich., a corporation of Michigan

Application February 12, 1945, Serial No. 117,908

Term of patent 14 years

(Cl. D9—2)

To all whom it may concern:

Be it known that George W. Walker and Kenneth A. Hopkins, both of whom are citizens of the United States of America and residents of Pleasant Ridge and Pontiac, respectively, in the county of Oakland and State of Michigan, have invented a certain new, original, and ornamental Design for a Converter for Suction Cleaners, of which the following is a specification, reference being had to the accompanying drawing, forming a part thereof and wherein:

Fig. 1 is a plan view of a converter for suction cleaners embodying our new design;

Fig. 2 is a rear elevational view thereof; Fig. 3 is a front elevational view thereof; and Fig. 4 is a side elevational view thereof.

The essential features of our design reside in the parts shown in full lines.

The stippling shown on the drawing is for purposes of shading only.

We claim:

The ornamental design for a converter for suction cleaners, as shown and described.

GEORGE W. WALKER.
KENNETH A. HOPKINS.
